HANDLE FOR SCREW DRIVERS AND OTHER
HAND TOOLS

Arthur E. Dianda, New York, N. Y.

Substituted for abandoned application, Serial No.
549,419, August 14, 1944. This application No-
vember 12, 1948, Serial No. 59,456

1 Claim. (Cl. 145—50)

1

This invention relates to new and useful improvements in rotary-head handles for screw drivers and other hand tools.

This is a substitute for my abandoned application filed August 14, 1944, Serial No. 549,419.

More specifically, the present invention contemplates the construction of a rotary-head tool handle characterized by having a part adapted to remain stationary and a part adapted to rotate when the screw driver is in use, the two parts being adapted to be held by different parts of the user's body.

Still further it is proposed to provide a handle as aforesaid having friction, roller or ball bearings between the parts and means securing the parts against accidental separation but permitting them to be disconnected when desired.

Another object of the present invention is to provide a screw driver with a handle as aforesaid having a ratchet permitting the handle to be turned by either part, the screw driver shaft upper end being capped by the top part and exposed when the top part is removed.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a view in elevation of a screw driver constructed in accordance with this invention.

Fig. 2 is an axial section through the screw driver.

Fig. 3 is an axial section through a screw driver constructed in accordance with a modification of this invention, the screw driver shaft being shown in full.

Fig. 4 is an enlarged detailed view of the top part of the screw driver shown in Fig. 3.

Fig. 5 is a fragmentary vertical section on the line 5—5 of Fig. 4.

Fig. 6 is a horizontal section on the line 6—6 of Fig. 4.

Fig. 7 is a fragmentary axial section of a handle constructed in accordance with a modification of this invention.

Fig. 8 is a fragmentary axial section of a handle constructed in accordance with a modification of this invention.

Fig. 9 is a fragmentary axial section of a handle constructed in accordance with a modification of this invention.

Fig. 10 is a view in elevation of a portion of

a screw driver employing either of the handles of Figs. 7—9.

Fig. 11 is a view in elevation, partly in section, of a handle constructed in accordance with a modification of this invention, two tools being indicated in dot-dash lines.

The screw driver, according to this invention, comprises a shaft 10 shaped at its lower end for insertion in the slot of a screw head. Shaft 10 is secured at its upper end in a roto-head handle including body 11, which may be, for instance, cast of plastic around the upper end of the shaft, the shaft having wings 12 preventing it from turning in the body. The lower end of the body 11 is conical and covered by a cap 13.

An axial bore 14 is formed in the top of the body and a roller bearing raceway groove 15 is formed in its top face around the bore 14. A normally stationary cap member 16 is disposed on top of the body 11 and has a pin 17 extended into the bore 14 and a ball bearing raceway groove 18 in its bottom face in line with groove 15. Ball bearings 19 are disposed in the grooves, frictionlessly supporting the member 16 on the body 11.

Pin 17 is formed with longitudinal flutes 20 aiding in securing it firmly in the cap member 16. At the lower end of the pin 17 there is an annular groove 21. A set screw 22 is screwed in a threaded orifice 23 in the body 11 and has its inner end rounded and disposed in the groove 21, holding the cap member 16 rotatably on body 11 but permitting their separation upon removal of the set screw 22.

The operation of the screw driver is as follows:

The person using the screw driver can bear against the cap member 16 with his hand or with the pit of his stomach, thereby pressing the shaft 10 firmly against the screw to be turned. With his other hand he can turn the body 11, thereby turning the screw. The ball bearings permit the body 11 to be rotated relative to the cap member 16 even though great pressure is exerted on the cap member 16. When desired, the cap member 16 can be removed for cleaning or replacement of the ball bearings 19 by removing the set screw 22. This set screw permits the rotation of the body 11 relative to the cap member 16 as it fits with clearance all around in the groove 21. As the cap member 16 is held stationary and is externally smooth, it prevents blisters from being caused. The roto-head handle, while shown as part of a screw driver, may be employed with other types of tools.

A screw driver constructed in accordance with

a modification of this invention is shown in Figs. 3-6, and it distinguishes from the screw driver of Figs. 1-2 in that the shaft 10' extends through and beyond the top of the body 11'. Body 11' has a flat top face on which is disposed a ball bearing raceway or cage 15' holding ball bearings 19'.

The upper end of the shaft 10' is provided with a row of ratchet teeth 24, one of which is extended, by means of a groove 25, to the top of the shaft 10'. The cap member 16' has a central bore 26 in which the upper end of the shaft 10' is disposed and a spring steel detent or drive strip 27 is secured in the member 16' with its inner end extending into the bore 26. The wall of bore 26 at one side of strip 27 is cut out, as is clearly shown in Figs. 5 and 6 providing a flared recess 28 permitting the inner end of strip 27 to bend, permitting the teeth 24 to idle past the detent when the body 11' and the shaft 10' are turned in a clockwise direction, as viewed in Fig. 6, relative to the cap member 16' and the detent 27. This inner end of strip 27 is adapted to contact with the ratchet teeth 24 in driving relation when the cap member 16' is turned in a clockwise direction, as viewed in Fig. 6, carrying the shaft 10' and the body 11' with it.

The operation of this form of device is as follows:

The screw driver may be employed exactly as was the screw driver of Figs. 1-2, that is to say, the cap member 16' held stationary while the body 11' is rotated, when a screw is being screwed into an object. During such operation, the ratchet teeth 24 merely idle past the free end of the detent 27. However, when the body 11' and the cap member 16' are gripped as a unit, the detent 27 engages the ratchet teeth 24 locking the parts 11' and 16' together against any possible relative rotation when the screw driver is being used to turn screws or the like into a piece of wood or similar material without pressure against the cap member 16'.

Furthermore, the detent 27 locks the cap member 16' to the body 11' against axial separation except when the detent 27 is disposed in the ratchet tooth 24 that opens into the groove 25. Member 16' may be removed from body 11' when the detent 27 is in ratchet tooth 24 that opens into the groove 25 by lifting the cap member 16' relative to the body 11'.

The removal of the cap member 16' exposes the top of the shaft 10'. This affords the added advantage that the user of the screw driver can hammer the top of the shaft 10' when necessary to start a stubborn screw or to clean out the slot of a screw when it is clogged with paint or other substance. The advantage of being able to hit the shaft 10' direct instead of hitting the top of the cap member 16' is that the member 16' won't become broken or disfigured and the body 11' will not be loosened on the shaft 10'.

The embodiments of the invention shown in Figs. 1-6 show simple types of roto-heads applied to screw drivers, it being understood that they may be applied to other types of tools. In Figs. 7-10 other types of roto-heads are shown which are also especially adapted for use with screw drivers, but may be used with other types of tools. These roto-heads are quite similar to each other but distinguish from each other mainly in that the roto-head of Fig. 7 is especially adapted for friction bearings, of Fig. 8 is especially adapted for roller bearings and of Fig. 9 is especially adapted for ball bearings. The handle

parts of these roto-heads may be made of plastic which is cast around the metal parts thereof.

The roto-head shown fragmentally in Fig. 7, constructed in accordance with a further modification of this invention is a surface bearing roto-head adapted for oil lubrication. It includes a stationary cap member 30 in which is threaded a stud 31 having a surface bearing plate 32 and a pin 33. The pin 33 is formed with an annular groove 34 in its lower end. A projection 35 on the cap member 30 extends into a recess in the plate 32 holding these two parts against relative rotation. The roto-head further has a body 36 formed with an axial bore in which is mounted a surface bearing plate 37 having a threaded cylindrical portion 38.

A projection 39 on body 36 extends into a recess in the plate 37 preventing relative rotation therebetween. A lock ring holder 40 is disposed in the bottom of the bore of the body 36 and is held therein by a force fit. A split lock ring 41 is disposed between the top of the holder 40 and a shoulder 38a formed on the inner face of the cylindrical portion 38 and engages the groove 34 of the pin 33, when the pin is inserted into the cylindrical portion 38 to removably rotatively attach the cap member 30 to the body 36. The member 30 has a skirt 42 overhanging the body 36, as is clearly shown in Fig. 7.

The operation of this roto-head is similar to that above described. The lock ring 41 permits the pin 33 to be pulled axially out of the body 36 separating the cap member 30 from the body 36. The surface plates 32 and 37 contact each other and may be lubricated so that they rotate relative to each other more easily. The oil flows into the body bore and lubricates the pin 33.

The roto-head shown fragmentally in Fig. 8, constructed in accordance with another modification of this invention, is a roller-bearing type roto-head, adapted for grease packed lubrication. It distinguishes from the roto-head shown in Fig. 7 in that it has roller bearings 43 between the bearing plates 32' and 37'. Other parts corresponding to similar parts of the roto-head of Fig. 7 are indicated by like references primed.

The roto-head shown fragmentally in Fig. 9, constructed in accordance with still another modification of this invention, is a ball bearing type roto-head adapted for grease packed lubrication. It distinguishes from the roto-head of Fig. 8 in that the pin 33'' has an annular groove 44 above its groove 34'' and the body bearing plate 37'' is made separately from the cylindrical portion 38''. The cylindrical portion 38'' has a shoulder above the locking ring 41'' similar to the shoulder of the roto-heads of Figs. 7 and 8 and a similar shoulder 45 below a locking ring 46 disposed in the groove 44. The adjacent surfaces of the bearing plates are provided with ball bearing raceways 47 in which are disposed ball bearings 48.

The wear plate 37'' of the body 36'' is separated from the cylindrical portion 38'' and merely rests in a complementary cavity formed in the top of the body 36'' and against the top end of the cylindrical portion 38'' as shown in Fig. 9. Frictional contact between the adjacent faces of the wear plate 37'' and the complementary cavity in the body 36'' will retain the wear plate 37'' against rotation in the assembled position shown in Fig. 9.

The pin 33'' is releasably retained in position within the cylindrical portion 38'' by engagement of the lock ring 41'' with the groove 34'' on the lower end of the pin 33''. The lock ring 46 is

merely freely projected into the top of the cylindrical portion 38" but bears against the bottom face of the wear plate 37". Thus, when the cap member 30" is separated from the body 36" by pulling axially upwards thereon, the pin 33" will move upwards in the cylindrical portion 38" away from the lock ring 41". At the same time, the lock ring 46 moves out of the top end of the cylindrical portion 38" and as it bears against the bottom face of the wear plate 37" it forces the wear plate 37" out of its complementary cavity in the top of the body 36" causing the wear plate 37" to be separated from the body 36" as a unit with the cap member 30. Thus, the wear plates 32" and 31" are held together preventing the ball bearings 48 from escaping from between the adjacent faces thereof when the cap member 30" is removed from the body 36". Should it, for some reason, be desirable to separate the wear plates 32" and 31" it is merely necessary to remove the lock ring 46 permitting the wear plate 32" to be slipped off the free end of the pin 33".

The cylindrical portion 38" is formed with knurling 52 at its periphery to prevent twisting. The cylindrical portion 38" may be cylindrical, rectangular or of any other shape in cross section.

The three roto-heads of Figs. 7-9 have several common features. One is that each of the pins has external helical lubricating grooves 51. Another is that the lock rings snap into place when the stationary cap member is pushed into position on the body member and similarly are forced back out of the way when the stationary cap member is pulled away from the body member to permit separation for cleaning and lubrication, or for replacement of worn ball or roller bearings. Each of the three roto-heads may have an outside appearance as shown in Fig. 10.

The roto-head shown in Fig. 11 is a socket wrench roto-handle. It is to be used with a socket set extension bar A or socket wrench bar handle B, indicated in dot-dash lines in Fig. 11. When used with a socket extension bar it is placed on one end of the bar, the roto-head being equipped with a hexagonal recess 49 in its bottom for this purpose. The socket to be used is placed on the other end of the bar. The roto-head is also provided with a hexagonal side recess 50 for use with a socket wrench bar handle. The roto-head may otherwise be constructed like either of the three roto-heads of Figs. 7-9.

While the roto-heads have been described as

being formed of metal parts around which plastic has been cast, it is obvious that the roto-heads may be made of other suitable materials such as wood or metal.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

15. A screw driver comprising a shaft having an end adapted to coact with the slotted head of a screw, a body secured on said shaft intermediate its ends, the other end of said shaft projecting above said body, a ball bearing assemblage disposed on the top face of said body surrounding said shaft, a cap member having an axial bore mounted on said projection of said shaft and resting on said ball bearing assemblage, said projection having a ring of ratchet teeth, and a ratchet detent in said cap member coacting with said teeth, one of said teeth being in line with a groove opening through the top end of said projection for sliding removal and assemblage of said ratchet detent with said teeth.

ARTHUR E. DIANDA.
